US0D1105151S

(12) **United States Design Patent** (10) **Patent No.:** **US D1,105,151 S**
(45) **Date of Patent:** **** Dec. 9, 2025**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Ian V. Bambao**, Pittsburg, CA (US); **Benjamin Thomas Christie**, Santa Barbara, CA (US); **Caroline J. Crandall**, Woodside, CA (US); **Wyatt R. Mitchell**, San Francisco, CA (US); **Ricky-Lee Richards**, San Francisco, CA (US); **Marissa Mei Lee Vergel De Dios**, Mission Viejo, CA (US)

(73) Assignee: **Apple Inc.**, Cupertino, CA (US)

(**) Term: **15 Years**

(21) Appl. No.: **29/956,928**

(22) Filed: **Aug. 9, 2024**

Related U.S. Application Data

(63) Continuation of application No. 29/841,277, filed on Jun. 3, 2022, now Pat. No. Des. 1,042,513.

CLAIM

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.
